UNITED STATES PATENT OFFICE.

BENJAMIN F. SUTTON, OF NEW YORK, N. Y., ASSIGNOR TO DANIEL C. PERKINS, OF PROVIDENCE, RHODE ISLAND.

ATOMIZER.

SPECIFICATION forming part of Letters Patent No. 281,942, dated July 24, 1883.

Application filed June 20, 1882. (Model.)

To all whom it may concern:

Be it known that I, BENJAMIN F. SUTTON, of the city, county, and State of New York, have invented certain new and useful Improvements in Atomizers, for converting liquids into vapor or spray, which improvements are fully set forth in the following specification and accompanying drawing.

My invention is an improvement on the bottle-pump or siphon-bottle patented by George Asmus, June 11, A. D. 1867, No. 65,527, whereby the said bottle-pump is changed into an apparatus for converting liquid into vapor or spray.

In the drawing annexed hereto is shown my atomizer, constructed with the usual rubber air-bulb, D, having valves at G G. The air passes through the pipe D' and cap F into the bottle at B, thus forcing the liquid H through the tube C.

The principal feature of my improvement consists in making one or more openings, A, in the liquid-tube C, to allow the compressed air or gas to mingle with the liquid during its course through the liquid-tube C, thus forming a combined liquid and air exit through one pipe, the supply of compressed air admitted to the tube C at the orifice A being regulated

by means of the adjustable valve E. When the orifice A is entirely closed by the valve E, 30 the atomizer becomes a bottle-pump, similar to that patented by the said George Asmus.

It is obvious that the fineness of the spray created when the orifice A is open can also be regulated by applying any of the well-known 35 valve attachments at I to the suction end of the tube C, thus enlarging or decreasing this opening to allow a proper proportion of liquid to enter the tube.

Having thus described my invention, I claim 40 as new and desire to secure Letters Patent for—

1. The combined liquid and air tube C when one or more openings are made in said tube above the surface of the liquid to allow compressed air or gas to mingle with the liquid during its exit, substantially as described, and for the purpose set forth. 45

2. The combination of the tube C, orifices A, and valves E and I, as described, and for the 50 purpose set forth.

BENJ. F. SUTTON.
